UNITED STATES PATENT OFFICE

2,169,349

TYPEWRITING MACHINE

Lewis C. Myers, Freeport, N. Y., assignor to Royal
Typewriter Company, Inc., New York, N. Y., a
corporation of New York

Application December 30, 1937, Serial No. 182,591

12 Claims. (Cl. 197—33)

This invention relates to new and useful improvements in typewriting machines generally, although more particularly to improvements in the means for adjusting the tensions of the type action springs and for indicating the amount of such adjustment, as shown in the patent to Myers 1,983,482, December 4, 1934. Reference also is made to the copending application of Anthony Utz, Serial No. 182,590, filed December 30, 1937.

10 In the Myers patent, a manually operable thrust screw is mounted in the rear of the machine frame for adjusting the anchor plate to which all of the type action springs are connected, and an indicator which is operable by 15 the anchor plate is located for observation at the side of the machine frame. The full force of the type action springs is directed against the manually operable adjusting screw and consequently these springs offer considerable resistance to the 20 thrust movement of the screw. Furthermore, by reason of the adjusting screw being located in rear of the machine, it is decidedly unhandy for the operator to effect an adjustment thereof and simultaneously observe the indicator which is at 25 the side of the machine.

Among the several objects of the present invention are to provide a manually operable element in close proximity to the indicator whereby the operator may readily adjust the combined 30 tension of the springs and simultaneously observe the effect of such adjustment, and to provide a manually operable screw which is freely adjustable for varying the combined tension of said springs.

35 With these and other objects in view which will more fully appear, the nature of the invention will be more clearly understood by following the description, the appended claims, and the several views illustrated in the accompanying 40 drawing.

In the drawing:

Figure 1 is a vertical section taken through a typewriting machine and showing the application 45 of my invention.

Figure 2 is a horizontal section taken on the line 2—2 of Figure 1.

Figure 3 is a horizontal section taken on the line 3—3 of Figure 1.

50 Figure 4 is a horizontal section taken on the line 4—4 of Figure 1.

Figure 5 is a detail vertical section taken on the line 5—5 of Figure 2.

Figure 6 is a detail elevation showing the indicator and the operating element therefor,

Figure 7 is an enlarged fragmentary view of the indicator dial, and

Figure 8 is a detail sectional view showing a modified arrangement wherein the dial is located wholly within the main frame. 5

Like reference numerals designate corresponding parts throughout the several figures of the drawing.

Referring to the accompanying drawing, I have illustrated my invention as being applied to 10 a Royal Standard typewriting machine, although it will be understood that the invention may be applied equally well to other known machines.

The typewriting machine includes a main frame A having a rear wall 5 and side walls 6, 6*. 15 Located within the main frame is a plurality of type actions each of which includes a type bar 7 pivoted at 8 on a segment 9, a key lever 10 pivoted at 11 on a cross bar 12 which is secured to the side plates of the frame, a front link 13 20 which is pivoted at 14 to a cross bar 14*, a link 15 which is pivotally connected to the key lever 10 and to the link 13, an intermediate lever 16 which is pivoted at 17 to the cross bar 12, a link 18 pivotally connected to the front link 13 and 25 the intermediate lever, and a link 19 which is pivotally connected to the intermediate lever 16 and to the heel of a type bar 7. A vertically disposed anchor plate 20 is journaled at its lower 30 end on spaced horizontal pivots 21 mounted in bearing lugs 22 which are rigidly connected to and extend forwardly from the rear wall 5 of the main frame, there being only one pivot and one lug shown. The upper end of the anchor plate 20 is provided with a forwardly extending 35 flange 23 having a plurality of openings 24, there being one opening for each type action. A universal bar 25 is mounted in the usual manner on the rear wall 5 of the frame and is connected by links 26 to the intermediate levers 16. A coil 40 spring 27 is disposed around each link 26 and has its forward end connected thereto and its rear end engaged in the corresponding opening 24 of the anchor plate 20. Normally the springs 27 exert a rearward pull on the intermediate levers 45 16 to thereby normally retain the key levers 10 and the type bars in their rest positions.

The right hand side wall 6 of the main frame is provided with an elongated opening 28 and removably mounted in said opening is a closure 50 plate 29 which is preferably formed of metal, although any other material may be employed if desired. The plate 29 is provided with an elongated horizontal opening 30, and a pointer 31 which is preferably integral with the plate, pro- 55

jects downwardly into the opening from the center of the upper edge of said opening. Disposed in close proximity to the opening 30, and preferably below the same, is a circular opening 32.

The anchor plate 28 is adjustable to and from the machine in order to vary collectively the tensions of the springs 27 and thereby vary the touch of the type actions. For this purpose a bracket 33 is rigidly mounted on the cross bar 12 adjacent the openings 30, 32 of the closure plate 28. This bracket includes spaced upper and lower plates 34 and 35 and journaled in these plates is a vertically disposed indicator shaft 36 having its upper end projecting above the upper plate 34. An indicator dial 37 of disc configuration is fixed to the upper end of the shaft 36 and projects slightly through the opening 30 of the closure plate 28. The disc is provided with a downwardly inclined beveled periphery 38 having a scale 39 thereon which is visible exteriorly of the plate 28 and is located in position for cooperation with the pointer 31.

25 Fixed to the indicator shaft 36 intermediate the upper and lower plates of the bracket 33, is a worm wheel 40 which is threadably engaged with a manually operable horizontal worm shaft 41 which is journaled in said bracket. One end of the shaft 41 projects outwardly through the 30 opening 32 and is provided with a finger knob 42.

A Link 43 is pivotally connected at its rear end as at 44 to a bracket arm 45 fixed to the upper end of the anchor plate 20. The front end of the link 43 is provided with a laterally extending arm 46 which overlies the indicator disc 37 and is pivotally connected thereto by means of an eccentrically positioned shoulder screw or pin 47 mounted on said disc.

The worm wheel 40 is provided with spaced shoulder stops 48, 48 adapted to respectively cooperate with a stop pin 49 fixed on the bracket 33 to thereby limit the rotations of the manually operable worm shaft 41 and also to maintain the scale 39 in cooperative relation with the pointer 31.

It will, therefore, be seen that when the worm shaft 41 is actuated by the operator, the indicator disc 37 will be rocked and the link 43 will rock the anchor plate 20 and thereby vary the combined tension of the springs 27. It will be also observed that by reason of the indicator and the manually operable element being in close proximity to each other and on the side of the main frame, the operator will have no discomfort in adjusting the springs and in observing the amount of adjustment.

In Figure 8, I have disclosed a modified construction wherein the dial 37 is located wholly within the main frame A. In this form the closure plate 29 of the side wall 6 is provided with an inwardly depressed portion 50 which includes an arcuate and inwardly inclined wall 51 and an upwardly inclined bottom wall 52 which overlies the scale 39 on said dial. The bottom wall 52 is provided with a view opening 53 which registers with the scale, and this opening is covered by a transparent plate 54 attached to said bottom portion.

The bevelled peripheral scale portion is readily viewable from a point above and outwardly beyond the side wall, and the location of the knob 42 below the dial as shown in Figures 1 and 6 enables the operator to adjust the spring tension without interfering with continued observation of the dial.

It is of course to be understood that the details of structure and arrangement of parts may be variously changed and modified without departing from the spirit and scope of my invention.

I claim:

1. In a typewriting machine, the combination with a main frame including a wall, of a plurality of type actions supported within said frame, an anchor plate pivotally mounted within said frame, springs respectively connecting the type actions and the anchor plate, an indicator dial rotatably supported within the frame and projecting outwardly through said wall, a manually operable element rotatably supported within the frame and projecting outwardly through said wall, and operating connections between the dial, the element, and the anchor plate for effecting conjoint movements thereof. 10 15

2. In a typewriting machine, the combination with a main frame including a wall, of a plurality of type actions supported within said frame, an anchor plate pivotally mounted within said frame, springs respectively connecting the type actions and the anchor plate, an indicator dial rotatably supported within the frame and projecting outwardly through said wall, the dial comprising a disc having a scale located thereon, a pointer fixed to the wall for cooperation with said scale, a manually operable element rotatably supported within the frame and projecting outwardly through said wall, and operating connections between the dial, the element, and the anchor plate for effecting conjoint movements thereof. 20 25 30

3. In a typewriting machine, the combination 25
with a main frame including a wall, of a plurality
of type actions supported within said frame,
an anchor plate pivotally mounted within said
frame, springs respectively connecting the type 40
actions and the anchor plate, an indicator dial
rotatably supported within the frame and pro-
jecting outwardly through said wall, a manually
operable element rotatably supported within the
frame and projecting outwardly through said 45
wall, operating connections between the dial and
the element, and a link pivotally connected at one
end to the anchor plate and having its other end
pivotally connected eccentrically to said dial. 50

4. In a typewriting machine, the combination with a main frame including a wall, of a plurality of type actions supported within said frame, an anchor plate pivotally mounted within said frame, springs respectively connecting the type actions and the anchor plate, an indicator dial rotatably supported within the frame and projecting outwardly through said wall, the dial comprising a disc having a scale thereon, a pointer fixed to said wall for cooperation with said scale, a manually operable element rotatably supported within the frame and projecting outwardly through said wall, operating connections between the disc and the element, and a link pivotally connected at one end to the anchor plate and having its other end pivotally connected eccentrically to said disc. 50 55 60 65 70 75 80 85

5. In a typewriting machine, the combination with a main frame including a wall, of a plurality of type actions supported within said frame, an anchor plate pivotally mounted within said frame, springs respectively connecting the type actions and the anchor plate, an indicator dial rotatably supported within the frame and projecting outwardly through said wall, a manually operable element rotatably supported within the frame and projecting outwardly 75 connected eccentrically to said disc. 65

through said wall, operating connections between the dial, the element, and the anchor plate for effecting conjoint movements thereof, and stop means for limiting the rotary movement of said dial.

5. In a typewriting machine, the combination with a main frame including a wall; of a plurality of type actions supported within said frame; an anchor plate pivotally mounted within said frame; springs respectively connecting the type actions and the anchor plate; and mechanism operatively connected to said anchor plate and including a vertical shaft rotatably supported within the frame adjacent said wall, an indicator dial fixed to said shaft and projecting outwardly through said wall, a worm wheel fixed to said shaft, and a manually operable and horizontally disposed worm shaft rotatably supported within the frame and engageable with said worm wheel, said worm shaft projecting outwardly through said wall.

6. In a typewriting machine, the combination with a main frame including a wall, of a plurality of type actions supported within said frame, an anchor plate pivotally mounted within said frame, springs respectively connecting the type actions and the anchor plate, a vertical shaft rotatably supported within the frame adjacent said wall, an indicator dial fixed to said shaft and projecting outwardly through said wall, a worm wheel fixed to said shaft, a manually operable and horizontally disposed worm shaft rotatably supported within the frame and engageable with said worm wheel, said worm shaft projecting outwardly through said wall, and a link pivotally connected at one end to the anchor plate and having its other end pivoted eccentrically to said dial.

7. In a typewriting machine, the combination with a main frame including a side wall having an opening, of type actions supported within said frame; an anchor movably mounted within said frame; springs connecting the type actions to the anchor; an indicator dial having a bevelled peripheral scale and being rotatably mounted within said frame with a portion of said scale being associated with said opening in a manner to be observable from a point above and outwardly beyond said side wall; a manually operable element; and operating connections between the dial, the element, and the anchor for effecting conjoint movements thereof.

8. In a typewriting machine, the combination with a main frame including a side wall having an opening, of type actions supported within said frame; an anchor movably mounted within said frame; springs connecting the type actions to the anchor; an indicator dial having a bevelled peripheral scale and being rotatably mounted within said frame with a portion of said scale being associated with said opening in a manner to be observable from a point above and outwardly beyond said side wall; a manually operable element; and operating connections between the dial, the element, and the anchor for effecting conjoint movements thereof.

9. In a typewriting machine, the combination with a main frame including a side wall having an opening; of type actions supported within said frame; an anchor movably mounted within said frame; springs connecting the type actions to the anchor; an indicator dial having

a bevelled peripheral scale and being rotatably mounted within said frame with a portion of said scale being associated with said opening in a manner to be observable from a point above and outwardly beyond said side wall; a manually operable element supported on said frame and projecting through said side wall at a point below said opening; and operating connections between the dial, the element, and the anchor for effecting conjoint movements thereof.

10. In a typewriting machine, the combination with a main frame including a side wall having an opening, of type actions supported within said frame; an anchor movably mounted within said frame; springs connecting the type actions to the anchor; an indicator dial rotatably mounted within said frame and having a bevelled peripheral scale inside of said side wall with a portion of said scale viewable through said opening from a point above and outwardly beyond said side wall; a manually operable element; and operating connections between the dial, the element and anchor for effecting conjoint movements thereof.

11. In a typewriting machine, a frame having a wall; type actions mounted within the frame; an anchor device movably supported on the frame; springs connecting the type actions with the anchor device, movement of the anchor device being effective to vary the tension of the springs; means for moving the anchor device; and a rotatable indicator dial connected to said anchor device and having a bevelled peripheral edge portion provided with scale markings, said frame wall being formed with an inwardly depressed portion having an inclined wall portion overlying the bevelled edge portion of the indicator dial, the inclined wall portion being provided with an opening through which the dial may be observed from outside the frame.

12. In a typewriting machine, a frame having a wall; type actions mounted within the frame; an anchor device movably supported on the frame; springs connecting the type actions with the anchor device, movement of the anchor device being effective to vary the tension of the springs; means for moving the anchor device; a rotatable indicator dial connected to said anchor device and having a bevelled peripheral edge portion provided with scale markings, said frame wall being formed with an inwardly depressed portion having an inclined wall portion overlying the bevelled edge portion of the indicator dial, the inclined wall portion being provided with an opening through which the dial may be observed from outside the frame; and a transparent closure for said opening.

LEWIS C. MYERS.
